Inventor

JOHN HORTON, OF ROCHESTER, NEW YORK.

Letters Patent No. 91,636, dated June 22, 1869.

IMPROVED TUYERE-ARCH FOR BLAST-FURNACES.

The Schedule referred to in these Letters Patent and making part of the same.

To all whom it may concern:

Be it known that I, JOHN HORTON, of Rochester, Monroe county, and State of New York, have invented a new and improved Mode of Protecting the Tuyeres and Surrounding Walls of a Blast-Furnace from the Action of the Fires; and I do hereby declare the following to be a full and exact description thereof, reference being had to the accompanying drawing, and to the letters of reference marked thereon:

The drawing is a perspective view; exposing the water-pipes on the bottom and right-hand sides.

My water-tuyere arch is made of a cast-iron shell, A, which is moulded in the desired form by a pattern, so constructed that a coil of iron pipe, b, may be placed in the mould, and the metal poured around it in a solid mass.

It may be shaped in any form best suited to the object, which is the protection of the tuyere and walls surrounding it from burning.

It is placed in the walls of the furnace just over the tuyere, the arch being of sufficient size to receive the tuyere and allow space for the packing, as usual.

The coils of water-pipe protrude through the arch, at both ends, one being for the inlet, and the other for

outlet, and by means of connecting them with other pipes, a supply of cold water is constantly to be passing through them, the coils being of a zigzag form, and following the general shape of the water-arch and bed-plate C.

Much trouble and expense are met with in protecting the tuyeres and walls of the tuyere-arch in blast-furnaces, as now constructed, from the effects of the severe fires necessary to the business.

The tuyeres and walls are constantly burning away, causing much delay for their repairs, which will be very greatly overcome by my improvement.

Claim.

What I claim as my invention, and desire to secure by Letters Patent, is—

The water-tuyere arch, or its equivalent, surrounding the tuyere of a blast-furnace, when constructed substantially as described, and for the purposes specified.

JOHN HORTON.
